UNITED STATES PATENT OFFICE

SIGMUND BECK, OF NUERMBERG, GERMANY

SHAVING BRUSH

Application filed August 24, 1927, Serial No. 215,012, and in Germany January 29, 1927.

This invention relates to improvements in shaving brushes, and particularly to means for securing the brush bristles together and in the socket of the brush handle.

5 The object of the invention is to provide a simple, reliable and inexpensive means for holding the bristles in such a secure manner that the fastening means will be proof against the bristles or fastening means becoming loose when subjected to sterilization or other high heat treatment.

In the accompanying drawing,—

Figure 1 is a longitudinal sectional view through a shaving brush showing one form 15 of the invention.

Figures 2 and 3 are similar views showing other forms of the invention.

In the construction shown in Figure 1, the inner ends of the bristles *a* are fitted within a 20 metallic ferrule or thimble *b*, and a plug *c* is centrally driven in between the ends of the bristles confined by the thimble. This plug is provided with an annular groove *d*. After the bristles, thimble and plug are assembled 25 the thimble is compressed or crimped to produce an annular indentation *e* on a plane coinciding with the groove *d*, whereby the intervening portions of the bristles are crimped and tightly compressed or clamped between 30 the indentation and walls of the groove and interlocked therewith. The plug is made of a material which will not be affected by high sterilizing temperatures. Instead of making the ferrule of metal, it may be made of 35 same composition material which will not be affected by sterilizing temperature, but may be softened by heat at higher temperatures so that it may be shaped to produce the crimp or indentation *e*. For securing the thus 40 clamped bristle tuft in the handle *f*, an anchor comprising a plurality of hook-shaped anchor pins *g* is provided. These pins are driven into the tuft before the thimble is crimped. The anchor pins project beyond 45 the confined ends of the bristles and are disposed in suitably spaced relationship to each other. The handle *f* is provided with a 50 socket having an outer portion *h* which receives the thimble and clamped ends of the bristles and an inner portion *h'* which re-

ceives the anchor pins *g*. Prior to the fitting of the tuft into the socket, the socket portion *h'* is filled with a suitable rapidly setting cement *i*, which when set will hold the clamped ends of the bristles firmly in position. As a 55 mechanical connection is provided for clamping the bristles and the anchoring cement *i* is arranged at a point removed from the exposed portions of the bristles and protected by the wall of the handle, the brush may be subjected to high sterilizing temperatures 60 without in any manner affecting the integrity of the connection of the bristles with the handle.

In the construction shown in Figure 2 the 65 anchor pins *g* are dispensed with and the plug *c* is provided with an integral anchoring stem *c'* which extends into the inner portion *h*² of the handle socket, which is of outwardly tapering form. The stem *c'* is shaped like a 70 screw, or provided with grooves or threads and a terminal head for a secure interlocking connection with the cement or setting agent *i'*. The tapering form of the socket portion *h*² here prevents any possibility of outward 75 displacement of the cement body.

In the construction shown in Figure 3 the 80 plug *c* is provided with a projecting anchor stem which is split to form a plurality of curved retaining prongs *c*² which are embedded in the cement filling *i'*, making a secure anchor. In this form of the invention the inner socket portion *h*² is also tapered as in the construction shown in Figure 2.

The mode of manufacture and construction described provides for the firm clamping of the bristles and assemblage of the parts in an easy, convenient, time-saving and inexpensive manner, and in the reliable holding of the bristles in the socket of the handle. With 90 this construction the brush may be sterilized repeatedly without in any manner affecting the integrity of the connection between the bristles and the handle.

Having thus fully described my invention, 95 I claim:—

1. A brush comprising a handle having a socket, brush bristles, an open-ended metal ferrule fitted in the socket and receiving the inner ends of the bristles, and a plug of a ma- 100

terial unaffected by sterilizing temperatures and fluids centrally arranged between the secured ends of the bristles and provided with an annular groove, the ferrule having an annularly indented portion disposed between its ends and crimping the bristles and clamping the same between said indented portion and the wall of the groove, and anchoring means extending from the plug and secured within the socket beyond the inner end of the plug.

2. A brush comprising a handle having a socket comprising an inner and an outer portion, brush bristles having their inner ends inserted in the outer portion of the socket, a plug fitted in the inserted ends of the bristles and provided with an annular groove, a sleeve fitted in the outer portion of the socket about the ends of the bristles and having an annular indentation between its ends and clamping the bristles between the same and the grooved portion of the plug, anchoring means carried by the secured ends of the bristles and extending into the inner portion of the socket, and a binder in the inner portion of the socket and securing the anchoring means therein.

3. A brush comprising a handle having a socket of unitary formation, the outer portion of which is of greater diameter than the inner portion, brush bristles having their inner ends fitted in the socket portion of larger diameter, a plug inserted in the bristles and provided with an annular groove, a sleeve fitted about the bristles in the portion of larger diameter of the socket and having an annular indentation disposed between its ends and clamping the bristles between the same and the grooved portion of the plug, anchoring means carried by the secured ends of the bristles and projecting into the socket portion of smaller diameter and a cement filler in said socket portion of smaller diameter and securing the anchoring means therein.

4. A brush comprising a handle having a socket of unitary formation and of relatively enlarged and restricted diameters at its outer and inner portions respectively, brush bristles having their inner ends inserted into the outer socket portion, a plug inserted in the bristles and having an annular groove and an anchoring extension, the latter projecting into the inner portion of the socket, a thimble encircling the inserted ends of the bristles and having an annular indentation disposed between its ends and clamping the bristles between the same and the grooved portion of the plug, and a binder in the socket portion of restricted diameter and securing the anchoring extension of the plug therein.

5. A brush comprising a handle having a socket of unitary formation and of relatively enlarged and restricted diameters at its outer and inner portions respectively, brush bristles having their inner ends inserted into the outer socket portion, a plug inserted in the bristles

and having an anchoring extension, the latter projecting into the inner portion of the socket, a thimble encircling the inserted ends of the bristles and clamping the bristles between the same and the plug, and a cementitious binder in the socket portion of restricted diameter and securing the anchoring extension of the plug therein.

6. A brush comprising a handle having a socket comprising an inner portion and an outer portion, a plug arranged within the outer portion of the socket, a metallic ferrule within the inner portion of the socket, brush bristles having their butts fitted in said ferrule and clamped between the same and the plug, anchoring means upon the plug extending into the inner portion of the socket, and means in said inner portion of the socket for holding said anchoring means.

In testimony whereof I affix my signature.

SIGMUND BECK.
